Gerhard L. Running and Ernest V. La Salle,
Minneapolis, Minn.

Application June 6, 1945, Serial No. 119,939

Term of patent 14 years

(Cl. D12—2)

To all whom it may concern:

Be it known that we, Gerhard L. Running and Ernest V. La Salle, citizens of the United States, residing at Minneapolis, in the county of Hennepin and State of Minnesota, have invented a new, original, and ornamental Design for a Hog Feeder, of which the following is a specification, reference being had to the accompanying drawing, forming part thereof.

Referring to the drawing:

Fig. 1 is a perspective view of a hog feeder showing our new design;

Fig. 2 is a side elevation thereof; and

Fig. 3 is a top plan view thereof.

We claim:

The ornamental design for a hog feeder, as shown.

GERHARD L. RUNNING.
ERNEST V. LA SALLE.
